UNITED STATES PATENT OFFICE.

AMOS G. CANBY, OF DETROIT, MICHIGAN.

ORNAMENT FOR THE CAPS OF RADIATORS.

1,362,672.

Specification of Letters Patent. Patented Dec. 21, 1920.

Application filed April 23, 1917. Serial No. 163,856.

To all whom it may concern:

Be it known that I, AMOS G. CANBY, a citizen of the United States of America, residing at Detroit, in the county of Wayne 5 and State of Michigan, have invented certain new and useful Improvements in Ornaments for the Caps of Radiators, of which the following is a specification, reference being had therein to the accompanying 10 drawings.

This invention relates to improvements in ornaments for the caps of radiators, pertaining more particularly to an ornament adapted to be rotated on a vertical axis by 15 the advancing movements of the motor vehicle on which the ornament is secured.

The invention consists in the matters hereinafter set forth, and more particularly pointed out in the appended claims.

20 In the drawings,

Figure 1 is a view in side elevation of a device that embodies features of the invention;

Fig. 2 is a view of a blade thereof;

25 Fig. 3 is a view in detail showing one method of attachment to the standard;

Fig. 4 is a view in elevation of a modification of the device;

Fig. 5 is a view in elevation of a further 30 modification of the device;

Fig. 6 is a view in detail of a modified form of blade;

Fig. 7 is a view in detail taken on or about line VII—VII of Fig. 4, and

35 Figs. 8, 9 and 10 are views in detail showing pivot supports for the fan blade.

As herein shown, a base 1 is adapted to be secured by bending into engagement with the cap 2, indicated in dotted lines, Fig. 1, 40 of the fill opening of a radiator. This connection may be effected by bendable prongs 3 that can be inturned under the margin of the cap. An upright spindle 4 is secured to the cap 1 by suitable soldering, brazing, 45 or the like, and affords a pivotal support for a two bladed vane 5 which may be fluted or otherwise arranged to carry an ornamental design, such as a flag or the like, with the blades crowned or made convex longitudinally in opposite directions, that is, with reverse curvature on the opposite sides of the spindle, as indicated in the plan view in Fig. 2, so that on movement through the air the blades revolve. An upper marginal flange 55 on the concave side of each blade directs air downwardly toward the cap.

As a matter of good mechanical construction, where the device is put up as indicated in Fig. 1, it is advisable to have the cap arranged with a rounded bearing rib 6 (see Fig. 3) and with a corresponding bearing margin indicated at 7 on the blade so as to allow for movement. Or as indicated in Fig. 4, the base may be a strip 8 adapted to be secured around the fill opening flange by bendable tongues 9 engaged to and folded back over the slotted ends of the strip. In such instance there may be an upright rod 10 with the lower portion bent laterally and secured to the strip, and with a split tube 11 secured on the upper end thereof in which the roughened body 12 of an upright spindle 13 may be inserted as a pivot for the blade 14.

Or, as indicated in Fig. 5 the spindle 15 may have set nuts 16 by which it may be secured in an opening in the cap 18 with the upper reduced end portion 19 of the spindle passing through an upper ear 20 of the blade 21, the end being afterward flattened to the spear head form indicated at 22 to retain the blade in position. Or the spindle may be tubular with the lower exteriorly screw-threaded portion 26 and a reduced inserted screwthreaded portion 23 which may practically be a machine screw, forced into the tube. This latter construction enables the blade to move upwardly under the influence of air which it forces downwardly and thus relieve the bearing on the base so as to greatly reduce the friction.

As shown in Fig. 5, the ornamental configuration of the vane is preferably such as to produce the appearance of a fluttering emblem as the car travels forward, and, in order to prevent more or less blurring of the emblem—especially where the emblem includes approximately horizontal stripe configurations—I prefer to locate the emblem configuration on but one of the wings 100 of a face of the vane, this being the trailing wing face on each face of the vane. For instance, in Fig. 5—assuming the view to represent the vane appearance from a position in front of the radiator—the advance 105 of the car will cause the vane to travel in a counter-clockwise direction on its axis, the unmarked wing face thus being the advance face, the emblem-carrying wing face trailing so that the configuration gives the appearance of an advancing flag fluttering as it advances. By omitting the representa-

tion on the opposite wing face, the illusion is not disturbed by the presence of a duplication of emblem representations. This relation is, of course, present on the opposite 5 face of the vane from that shown in Fig. 5, with the result that each wing has one of its faces carrying the emblem representation with the opposite face of the wing free from such representation, the dimensions of the 10 representation on each vane face being included within the face of but one of the wings.

The illusion thus created is enhanced by the use of the flanged portions 17 which 15 tend to produce a pocket effect on that face of the vane which is subjected to the air pressure during the advance of the car, thereby insuring that proper rotation of the vane will be had regardless of the speed of 20 travel of the car; the succession of emblem presentations to the eye produced by the rapid substitution of one emblem face for the preceding one, increases the illusion effect.

25 Obviously, changes in the details of construction may be made without departing from the spirit of my invention and I do not care to limit myself to any particular form or arrangement of parts.

30 What I claim is:—

1. An ornament for the caps of automobile radiators comprising an upright spindle, means for detachably securing the spindle in upright position on a radiator cap, and a 35 two winged blade journaled on its transverse

axis of symmetry on the spindle, the wings thereof being proportioned and arranged to cause rotation of the device when the machine on which it is mounted is advancing, said blades carrying the representation of a 40 flag or emblem on each of its opposite faces with the representation on each face limited to the dimensions of one of the wings and with the representation of one face carried by a different wing from that which carries 45 the representation on the opposite face of the blade.

2. An ornament for the caps of motor vehicle radiators comprising an upright spindle adapted to be secured to the cap to project 50 thereabove, and a two-winged vane journaled on its transverse axis of symmetry on the spindle, said vane having a configuration to cause rotation thereof by the advancing movement of the vehicle, the vane carrying 55 marginal flanges at the top and outer edge of each wing, with the marginal flanges of a wing projecting substantially transverse to the general plane of the wing and in the direction of its advancing face, whereby the 60 advance face of the leading wing will carry a pocket formation effective to carry the vane through its revolutions.

In testimony whereof I affix my signature in the presence of two witnesses.

AMOS G. CANBY.
